UNITED STATES PATENT OFFICE.

MORRIS LOWY, OF NEW YORK, N. Y.

FOLDING COT.

1,246,290.

Specification of Letters Patent. Patented Nov. 13, 1917.

Original application filed August 13, 1915, Serial No. 45,334. Divided and this application filed August 25, 1916. Serial No. 116,851.

To all whom it may concern:

Be it known that I, MORRIS LOWY, a citizen of the United States, and a resident of the city of New York, in the county of 5 New York and State of New York, have invented certain new and useful Improvements in Folding Cots, of which the following is a specification:

The present invention relates to folding 10 cots, and is divided out of my application for U. S. Letters Patent, Serial No. 45,334, filed Aug. 13, 1915.

One of the objects of the invention is to simplify the construction of devices of this 15 kind by providing a structure which is light, durable, simple, inexpensive to manufacture, and which can be readily so folded that it will occupy a small space.

Another object of the invention is to produce a folding cot comprising a pair of foldable sections which are connected by a short intermediate section, each of said foldable sections having a pair of legs, which are so connected by simple means with said middle 25 section that by one movement both foldable sections as well, as the legs may be folded into a compact upright structure, or opened in readiness for use, and when open the cot will be maintained in its position against 30 premature closure.

With these and other objects in view, which will more fully appear as the nature of the invention is better understood, the same consists in the combination, arrangement, and construction of parts hereinafter described, pointed out in the appended claims and illustrated in the accompanying drawings, it being understood that many changes may be made in the size and proportion 35 of the several parts and details of construction within the scope of the appended claims without departing from the spirit or sacrificing any of the advantages of the invention.

A few of the many possible embodiments 45 of the invention are illustrated in the accompanying drawings, in which:

Figure 1 is a side elevation of a cot constructed in accordance with the present invention in its extended position; Fig. 2 is a plan view thereof, part of its bed spring or mattress being removed in order to more clearly show the construction; Fig. 3 is a side elevation of the cot in its folded position; Fig. 4 is a front elevation thereof, also

folded; Fig. 5 is a side elevation of a modification of the connecting means between the foldable sections and the middle section of the cot; Fig. 6 is a section taken on line 6—6 of Fig. 5; and Fig. 7 is a side elevation 60 of a further modification of the connecting means between the foldable sections and the middle section of the cot.

Referring now more particularly to Figs. 1 to 4, inclusive, the numeral 10 indicates the top frame of the cot. This frame comprises an oblong structure, formed of two similar sections 11 and 12, each of which is constructed, preferably, of angle irons. The section 11 comprises side rails 13, the outer ends of which are connected by an end rail 14. In a similar manner consists the section 12 of side rails 15, which are connected at their outer ends by an end rail 16. The side rails of both sections of the top frame are 70 united by a short middle section 17, to which the inner ends of the side rails are pivoted at 18. The middle section comprises two bracket-like structures 19, which are connected by a cross-rod or brace 20, the latter being disposed a substantial distance below the side rails of the frame sections, so as to leave sufficient clearance under the bed bottom to enable the latter to sag under the weight of a person lying thereupon without 75 his body striking or contacting with the said cross-rod. Upon the vertical portions of the bracket-like structures 19 are formed lugs 21, to which the side rails of the frame sections are pivoted. The inner ends of the 80 side rails of the frame sections overlap and rest upon these lugs when the cot is in its extended position, the horizontal portions 22 of the brackets then filling the gaps between the inner ends of the horizontal flanges of the side rails.

The top frame carries a bed spring, which may serve at the same time as a mattress. For this purpose the said frame is provided with a plurality of apertures 10' in the horizontal flanges of the angle irons constituting said frame. Each of these apertures is engaged by one end of a spring 23, the other end of which is attached to a sheet 24 of a suitable fabric or other flexible material. 90 This structure forms a combined mattress and spring, and is adapted to be folded with the cot as the latter is brought into the positions shown in Figs. 3 and 4 of the drawings.

Each of the frame sections 11 and 12 is supported by a pair of legs 25, which are provided with casters 26 for a well-known purpose. Each pair of legs is braced by a 5 pair of tie-rods, in the present case by two rods, denoted by the numerals 27 and 28. These rods extend horizontally and transversely of the cot, those denoted by the numeral 27 being disposed near the upper 10 ends of the legs and those indicated at 28 near their lower ends. One pair of legs is pivoted at 29 to the side rails 13, and the other pair at 30 to the side rails 15. To the brace 20 is attached a downwardly projecting bar 31, upon which are formed two lugs 32, to which are pivoted at 33 links 34, the other ends of which are fulcrumed at 35 to the tie-rods 28. These links extend in the longitudinal axis of the cot, each of the 15 same connecting one pair of legs with the bar 31, the latter being centrally arranged upon the brace or cross-bar 20. Upon the bar 31 are formed stops 36, which rest upon the links 34 when the cot is in its extended 20 position.

The cot may be provided with end-pieces, that is to say, a head- and foot-piece, so as to give it the appearance of a normal bedstead. These end-pieces are denoted by the 25 numeral 37, and comprise each a substantially oblong frame, the vertical portions 38 of which are pivoted near their lower ends at 39 to standards 40, the latter being rigidly attached to the side rails of the cot. 30 The head- and foot-piece have their lower horizontal bars 41 projecting below the side rails, and to the central portions of these bars are pivoted at 42 bent links 43, the other ends of which are fulcrumed at 44 to 35 the respective tie-rods 27.

Upon the bar 31 is slidably mounted below the lugs 32 a sleeve 45, which is connected with the links 34. More particularly, it is connected with each link by a 40 short link 46, that is pivoted at 47 and 48 to the sleeve 45 and to a link 34, respectively.

The operation of this device is as follows: In order to fold the cot, the operator 45 takes hold of the top frame sections 11 and 12, and moves the central portions of the same upward, swinging them around the pivots 18, which results, due to the connections between the legs 25 and the bar 50 55 31, in a swinging of the legs 25 around the pivots 29 and 30, until the legs abut against the respective side rails, and the said side rails are brought in parallel relation to each other into the positions shown in Figs. 3 60 and 4 of the drawings. At the same time it is to be observed that, as the legs 25 are moved into the positions indicated, the links 43 shift the end pieces 37 around their pivots 39, until they are brought into substantially 65 parallel relation to the side rails. If de-

sired, an upholstered mattress and the bed spring clothing can also be folded with the frame.

The short intermediate section 17 maintains the two folding sections of the cot 70 suitably spaced, to provide proper place for the legs and the links when the structure is folded. Inasmuch as the inner ends of the side rails of the two folding sections of the cot rest upon the lugs 21, and the stops 36 75 rest upon the links 34, the inner ends of the top frame sections will be prevented from dropping below the level of the outer ends thereof, or in other words, the lugs and stops will prevent the cot sections from swinging 80 out of alignment under weight. The intermediate section thus not only serves to maintain the two sections of the cot suitably spaced, but, by reason of the lugs and stops formed thereon, it acts as a stop to maintain the frame sections in alignment. 85

When the cot is being folded, the connection between the links 34 and the sleeve 45 will cause the bar 31 to remain during the folding operation in a vertical position 90 thereby greatly facilitating the folding operation.

It is to be noted that, while the structure herein described comprises but a single pair of legs for each folding section, so that the 95 cot, as a whole, has but four legs, these legs are so located and organized as to efficiently support the frame sections; moreover, these legs are so connected with the frame sections and with the folding head and foot that by 100 one movement both the sections as well as the legs and the head and foot may be folded into a compact upright structure, or opened in readiness for use, and when open the cot will be maintained in position against pre- 105 mature closure.

A modification of the invention is illustrated in Figs. 5 and 6. In this case the sleeve 45 and the links 46 are missing. Furthermore, instead of two pivots there is 110 only a single pivot provided for connecting the links 34 with the bar 31. Otherwise the construction and operation of the apparatus are the same as of that above described.

In the modification shown in Fig. 7 of 115 the drawings, the links 34 are connected by springs 49 with projections 50 upon the downwardly extending bar 31. These springs will maintain the bar 31 in vertical position during the folding operation. 120

What I claim is:

1. In a folding cot comprising a pair of foldable cot sections, a short middle section pivotally connected to the inner ends thereof, said foldable cot sections folding transversely of the cot by lifting such inner ends and thereby allowing the outer ends to drop and close toward each other, and a pair of legs pivoted to each of said foldable sections, the combination of a downwardly ex- 130

tending bar attached to said middle section, said bar being shorter than said legs and provided with stops, and a link connecting the legs of each foldable section with the 5 bar on said middle section.

2. In a folding cot comprising a pair of foldable cot sections, a short middle section pivotally connected to the inner ends thereof, said foldable cot sections folding 10 versely of the cot by lifting such inner ends and thereby allowing the outer ends to drop and close toward each other, and a pair of legs pivoted to each of said foldable sections, the combination of a downwardly extending

bar attached to said middle section, said bar 15 being shorter than said legs and provided with stops, a link connecting the legs of each foldable section with the bar on said middle section, said links being disposed substantially in the longitudinal center line of 20 said cot and said stops resting upon said links when the cot is extended, and means for maintaining said bar in its vertical position during the folding operation.

Signed at New York, in the county of 25 New York and State of New York, this 23rd day of Aug., A. D. 1916.

MORRIS LOWY.
